UNITED STATES PATENT OFFICE.

JESSE R. POWELL, OF CHICAGO, ILLINOIS, ASSIGNOR TO ARMOUR & COMPANY, OF CHICAGO, ILLINOIS, A CORPORATION OF ILLINOIS.

SOAP STABILIZATION.

No Drawing.

Application filed December 24, 1926. Serial No. 156,989.

My invention relates to soap stabilization and it has particular relation to the prevention of decomposition or rancidification of soap.

Among the objects of the invention are improved methods of manufacturing soaps, or soap products, whereby soap rancidification or decomposition is prevented, and an improved soap product embodying a stabilizer for the same purpose.

Much trouble is experienced in the manufacture and distribution of soap on account of the tendency of some soaps to decompose or become rancid. The difficulties are particularly pronounced in case of soaps or soap products made from fats which rapidly develop rancidity, such as cottonseed oil, cottonseed oil foots, commercial greases, and the like.

20 In the Patent No. 1,542,438, to Robert E. Devine, assigned to the assignee of the present application, there is described a process of stabilizing soap and an improved stable soap product utilizing a small quantity of an aromatic amine, such as diphenylamine, as a stabilizing agent.

According to my present invention, I use as a stabilizing medium, a different class of product than that disclosed in the foregoing patent. I have found, namely, that soap decomposition or rancidification will be prevented by incorporating in the soap a small quantity of a condensation product of an aromatic amine with an aliphatic aldehyde, such as acetaldehyde-aniline, formaldehyde-aniline, and the like. In order to secure the stabilizing effect, the stabilizing agent may be added to the soap at any of the stages of its manufacture, and very good results are also obtained if the stabilizing agent is added to the raw product from which the soap is made, that is, to the oils and fats. In the latter case, that is, when my improved stabilizing agent is added to the raw fats which

45 tend to develop rancidity, such as cottonseed oil, cotton-seed oil foots, and the like, rancidity and decomposition of such fats will be prevented, and the stabilizing action will also be effective during the further chemical

processes to which the fats are subjected in 50 the course of their conversion into the soap, so that the resulting soap product will be stable, and free from any tendency to decompose or become rancid.

The amount of the improved stabilizing 55 agent that is necessary in order to secure a stable soap, is relatively small. The addition of approximately 1/100th or 1/50th to 1/2 of 1%, by weight of the soap product when in the molten state, will in most cases 60 be sufficient. I have secured very good results and a perfectly stable soap by adding approximately 1/25th of 1% of acetaldehyde-aniline to the ordinary soap product made with the kettle process. The word 65 small in the claims as applied to the amount of stabilizing agent, means that a sufficiently small quantity of stabilizing agent is present, usually, in the above proportions, to stabilize the soap.

As a practical example of carrying out my invention, the fat from which the soap is to be made, for instance, cottonseed oil, lard, corn oil, olive oil, or other oil or fat, is directly saponified, or may be hydrolyzed, 75 for example, by means of sulphuric acid, sulfo-fatty acid compounds, or the like, and the resulting fatty acid removed by steam distillation.

The fatty acid is then converted into a 80 soap for example, by the usual kettle process being neutralized, preferably with soda, boiled and washed in the usual manner, resulting in a soap stock of a well known commercial type. The soap obtained from 85 either of the foregoing processes may then be washed and drawn off, and while in this state I am adding thereto about 1/25th of 1% of acetaldehyde-aniline. The soap is then dried in the usual manner and may 90 then be marketed in cakes, in flakes, or any other form, as desired.

As pointed out above, my improved stabilizing agent will be effective if added during 95 any other stage of the process of the manufacture of the soap. For instance, I may add the corresponding amount of the stabilizing agent, such as acetaldehyde-aniline, to

the oils, or fats, prior to the saponification. The oils and fats so treated may then be saponified just as is the case with oils that have not been stabilized, and the resulting soap product will then be found to be stable, similarly to the soap to which the stabilizing agent was added while in the molten state. On the other hand I have also secured good results by mixing or otherwise incorporating the stabilizing agent into the soap flakes, or into the solidified soap, for instance, while it is being passed through the soap mill, or plodder. In general, any method whereby the stabilizing agent is suitably incorporated in the final soap product will be found effective in preventing decomposition, or rancidification, thereof.

Instead of incorporating in the soap the condensation product of the aromatic amine and the straight-chain aldehyde, I may incorporate first one ingredient, and then another ingredient, in the soap, at different times. The two substances will then react to form the condensation product while incorporated in the soap body. Thus, for instance, I may add the amine to the raw oil or fats prior to the saponification thereof, and add the aldehyde to the saponified product obtained therefrom when drawn off from the kettle.

In its broad aspects, my invention is not restricted to the use of the specific substances enumerated above. On the contrary, other condensation products of aromatic amines with straight-chain aldehydes, may be used instead, with very good results.

I have found that soaps having embodied therein a stabilizing agent according to my invention, will not decompose or become rancid where similar soaps being made without the stabilizing agent would become rancid in a very short time, for instance, approximately two weeks. My improved stabilizing agent is also effective in preventing discoloration of the soap, or spotting of the same, which is found very objectionable in commercial soaps.

The expressions "incorporating in the soap" or "incorporating in the soap product" used in the accompanying claims, include any of the methods described above of adding the stabilizing agent to the final soap or soap product. There are three methods specifically disclosed in the specification, namely: (1) Mixing the condensation product with the raw fat; (2) mixing the condensation product with the finished soap; and (3) mixing the aromatic amine or aliphatic aldehyde with the raw oil or fats prior to saponification and then adding the other ingredient to the final soap, whereupon the two are caused to react to form a condensation product. Those methods in which the condensation product, or the ingredients which will form the condensation product,

are added before or during the soap making reaction are specifically included in the claims by the expression "intermixing or incorporating a condensation product * * * during the saponification".

The aniline may be replaced in whole or part by toluidine, xylidine, and other ammoaryl and aralkyl derivatives. These amines may also contain substituent groups, as for example nitro, sulpho-, chloro-, bromo-, hydroxy-, carboxy-, etc. groups. The formaldehyde or acetaldehyde may also be replaced in whole or part by butylaldehyde, propylaldehyde, furfuraldehyde, and other similar aldehydes.

I claim:

1. The method of stabilizing soap which comprises intermixing therewith a condensation product of aromatic amines with aliphatic aldehydes.

2. The method of stabilizing soap which comprises incorporating in the soap product an aromatic amine and an aliphatic aldehyde and reacting the two to form a condensation product.

3. The method of stabilizing soap which comprises embodying therein acetaldehyde and aniline and reacting the two to form a condensation product.

4. The method of manufacturing a stable soap which comprises incorporating in said soap the condensation product of acetaldehyde and aniline.

5. The method of manufacturing soap which comprises mixing therewith between 1/100th and 1% of a condensation product of an aromatic amine and an aliphatic aldehyde.

6. The method of manufacturing soap which comprises incorporating therein from 1/50th to 1/2 of 1% of a condensation compound of an aromatic amine and an aliphatic aldehyde.

7. The method of manufacturing soap which comprises incorporating therein from 1/50th to 1/2 of 1% of a condensation compound of aniline and acetaldehyde.

8. A soap stabilized by a condensation product of an aromatic amine and an aliphatic aldehyde equal to 1/100th to 1% of the soap.

9. A soap stabilized by a condensation product of acetaldehyde and aniline equal to 1/50th to 1/2 of 1% of the soap.

10. A soap derived from fatty acids having a high tendency to rancidify stabilized by a condensation compound of an aromatic amine and an aliphatic aldehyde of about 1/50th to 1/2 of 1% of the soap.

11. A soap derived from fatty acids having a high tendency to rancidify stabilized by a condensation compound of an acetaldehyde and aniline of about 1/50th to 1/2 of 1% of the soap.

12. A soap stabilized by a small amount

of a condensation compound, of an aromatic amine and an aliphatic aldehyde.

13. A method of stabilizing soap which comprises intermixing a condensation product of an aromatic amine and an aliphatic aldehyde during the saponification.

14. In a method of stabilizing soap the

step of incorporating a condensation product of an aromatic amine and an aliphatic aldehyde with the raw fats prior and preparatory to saponification. 10

In testimony whereof I have hereunto subscribed my name.

JESSE R. POWELL.
